DESIGN FOR A TEXTILE FABRIC

Max U. Juestrich, Ridgefield, N. J., assignor to
The American Fabrics Company, Bridgeport,
Conn., a corporation of Connecticut

Application February 2, 1935, Serial No. 55,212

Term of patent 3½ years

To all whom it may concern:

Be it known that I, Max U. Juestrich, a citizen of the United States, residing at Ridgefield, county of Bergen, and State of New Jersey, have invented a new, original, and ornamental Design for Textile Fabric, of which the following is a specification, reference being had to the accompanying drawing, forming part thereof.

The figure is a plan view of a piece of textile fabric embodying my new design.

The light lines shown at A in the accompanying drawing indicate the body of the fabric.

I claim:

The ornamental design for textile fabric, substantially as shown and described.

MAX U. JUESTRICH.
